UNITED STATES PATENT OFFICE

2,433,324

CABLE CONVEYOR BUTTON OR BLOCK

Cyril R. Rogers, Port Arthur, Ontario, Canada,
assignor to Provincial Paper Limited, Toronto,
Ontario, Canada, a corporation of the Province
of Ontario

Application November 7, 1945, Serial No. 627,111
In Canada September 21, 1944

3 Claims. (Cl. 198—176)

1

In the handling of material of various kinds, such as pulpwood, logs, wood blocks, rock, gravel and the like, it is usual to convey the material along a stationary trough or track by means of a rope or cable, the latter having thereon a plurality of "buttons" or attachments which travel with the rope or cable and engage the material to be conveyed to move the latter along the trough or track.

The cable is moved along the trough or track by motive power transmitted to the cable through sheaves, the cable being made endless similar to a power transmission belt.

The "buttons" or attachments are subject to considerable wear and therefore often have to be replaced, and in view of their construction have not only to be replaced as a whole, but are also very troublesome to apply and hold in place.

The object of my present invention is to devise a "button" which will avoid the use of clamping bolts and nuts, which will give increased wearing surface without increase in weight, in which only the wearing surfaces need be replaced, and in which the time required for replacement is considerably reduced.

I attain my object by means of the constructions hereinafter described and illustrated in the accompanying drawings in which

Fig. 1 is a perspective view of a part of a trough and cable with my improved button applied thereto and a tool for positioning and removing the button;

Fig. 2 is an enlarged side elevation of the button;

Fig. 3 an enlarged plan view of the button,

Fig. 4 an enlarged end elevation of the button.

In the drawings like numerals of reference indicate corresponding parts in the different figures.

A indicates part of a conveyor trough, B the conveyor cable and C the button or attachment, and D a tool for use in removing or applying a button.

The button C is preferably cylindrical in form and comprises a pair of body members 1 and 2 which are shaped to form between them a hole 3 for the cable B. The member 1 is formed with lugs 4^a and 4^b, while the member 2 is formed with correspondingly shaped recesses 5 and 5^b to receive said lugs and prevent relative endwise movement between said members 1 and 2.

A part of the cable passage 3 in the member 1 is formed with a concave recess 6, while in the part of the cable passage 3 in the member 2 is formed a convex projection 7, the purpose being to cause a bending or crimping of the cable B

2

which tends to resist endwise movement of the button on the cable.

The body members 1 and 2 are held in cable engaging position by clamping members 8 and 9, body member 1 being provided with wedge shaped longitudinal ribs 1^c and 1^d at each side thereof and body member 2 being provided with complementary wedge shaped longitudinal ribs 1^b and 1^d at each side thereof. Respective sides 11 and 12 of ribs 1^c and 1^d of member 1 are longitudinally inclined in one direction and respective sides 13 and 14 of ribs 1^b and 1^d of member 2 are longitudinally inclined in a diverging direction to provide a wedge-shaped structure between each pair of the opposed sides 11 and 13 and 12 and 14. Clamping members 8 and 9 are provided with complementary wedge-shaped recesses 15 and 16 each adapted to engage and embrace a corresponding pair of ribs 11 and 13 or 12 and 14.

20 By moving the clamping sections in one direction, the co-operating inclined or wedging surfaces on the body sections and clamping members tend to increase the grip of the body sections on the cable, while movement in the reverse direction tends to release the grip.

25 The body sections 1 and 2 are preferably provided with heads 1^a and 2^a which may be of complementary semi-cylindrical shape. Such heads limit the longitudinal movement of the clamping members with respect to the body members and constitute protective abutments therefor. If a cable, having the button described mounted thereon, is drawn in a direction wherein the heads 1^a and 2^a constitute the leading surface of the button, such heads will protect the clamping members from impact with material being conveyed or other objects to prevent accidental dislodgment thereof from the body members. If the cable is drawn in the opposite direction, wherein 30 the exposed ends of the clamping members constitute a portion of the leading surface of the button, the heads on engagement with the inner ends of the clamping members, will prevent further longitudinal movement thereof despite impact with conveyed material or other objects.

35 To facilitate positioning and removal of the button a special tool such as D may be provided. This is in the form of a vise having a pointed projection 111 on one of the jaws 112 adapted to project into a notch 10 in one of the body sections, while through the other jaw 113 is threaded a screw 114 the point 115 of which engages in a similar notch 11 in the other body section. The screw is provided with a suitable handle 116 for 40 operating purposes. By tightening down on the

screw the body parts may be held in place while the clamping members are removed or replaced.

It will be seen that the button employs no bolts or nuts. It will also be seen that most of the wear is taken by the wearing or clamping members 8 and 9 and these may be very easily removed and replaced when necessary.

What I claim is:

1. A material-conveying block for attachment to conveyor cables, said block having a substantially uninterrupted outer surface and comprising a body having two complementary parts, said parts having meeting faces longitudinally recessed to receive a cable, each part having at each side adjacent the meeting face a longitudinal 15 tapered rib undercut at the side remote from the meeting face, and a radially extending portion between the ribs, said radially extending portion having a minor face constituting a portion of said outer surface of the body, and a pair of clamping members each having a groove therein shaped to receive one of the ribs on one body part and the adjacent rib on the other body part, said clamping members having outer faces constituting a major portion of said outer surface of the body.

2. A material-conveying block for attachment to conveyor cables, said block having a substantially cylindrical outer surface and comprising a body having two complementary parts, said parts having meeting faces longitudinally recessed to receive a cable, each part having at each side adjacent the meeting face a longitudinal tapered rib undercut at the side remote from the meeting face, and a radially extending portion be-

20

25

tween the ribs, said radially extending portion having plane side surfaces and a curved outer face constituting a minor portion of said cylindrical outer surface of the body, and a pair of clamping members each having a groove therein shaped to receive one of the ribs on one body part and the adjacent rib on the other body part, said clamping members having inner faces engaging said plane side surfaces of the body parts and outer curved faces constituting the major portion of said cylindrical outer surface of the body.

3. A material-conveying block as defined in claim 2, each said body part having a substantially semi-cylindrical head portion, said head portions overlying the end surfaces of the clamping members and being engageable thereby to limit movement thereof with respect to the body parts.
